UNITED STATES PATENT OFFICE.

EDWARD D. GUDEBROD, OF POTTSTOWN, PENNSYLVANIA.

SLUB-CATCHER FOR SILK-WINDING MACHINES.

1,289,160.

Specification of Letters Patent. Patented Dec. 31, 1918.

Application filed August 31, 1917. Serial No. 189,061.

To all whom it may concern:

Be it known that I, EDWARD D. GUDEBROD, a citizen of the United States, residing at Pottstown, in the county of Montgomery 5 and State of Pennsylvania, have invented certain new and useful Improvements in Slub-Catchers for Silk-Winding Machines, of which the following is a specification.

My invention consists of improvements in 10 slub catches for silk winding machines, the object of the invention being to automatically stop the winding when a slub or knot engages a contact fork, and also stop the winding when the thread breaks or the end 15 is reached.

A further object is to provide an electrically controlled stop mechanism of the character stated which can be attached to the ordinary winding machine in general use, and 20 which is so arranged as to prevent wasting of the current when the machine is stopped.

With these and other objects in view, the invention consists in certain novel features of construction and combinations and arrangements of parts as will be more fully 25 hereinafter described and pointed out in the claim.

In the accompanying drawings:

Figure 1 is a diagrammatic view partly 30 in elevation illustrating my improvements.

Fig. 2 is a broken view partly in section on the line 2—2 of Fig. 1.

Fig. 3 is a view in section on the line 3—3 of Fig. 1.

Fig. 4 is an enlarged view in elevation partly in section showing the mounting of the contact fork.

Fig. 5 is an edge view of Fig. 4; and

Fig. 6 is a fragmentary view of the opposite side of the device shown in Fig. 4.

My improvements are to be used in connection with an ordinary type of winding machine, and I have illustrated only such features of the winding machine as are necessary to illustrate my invention.

1 represents a foot lever having a crank arm 2 movable thereby and connected by a rod 3 with a bell-crank-lever 4. A spring 5 is located around the rod 3 between a fixed 50 part 6 and a collar 7 on rod 3, so that the spring exerts a pressure on the bell-crank-lever, holding it in normal position.

The bell-crank-lever 4 is connected to a bar 8 having slots 9 therein through which 55 pins 10 project to limit the sliding movement of the bar. The bar 8 adjacent its

free end is provided on its upper face with a shoulder 11 against which a roller 12 on a pivoted link 13 is adapted to bear and hold the bar in its operative position. 60

14 is a kick-off lever pivotally supported between its ends as shown at 15, and at one end is weighted as shown at 16, and provided with a finger 17 extending under the link 13. The other end of the kick-off lever 14 is 65 provided with a hook 18 having a laterally projecting lug 19 thereon engaged by a lever 20. This lever 20 is pivotally connected at one end to a fixed part 21, and constitutes an armature attracted by an electro-magnet 22 below the same, so that when the magnet is energized, it operates to elevate the link 13, release bar 8, and allow spring 5 to move the bar inwardly. 70

23 represents a spool which is driven by 75 the machine, and the mechanism above described omitting the lever 20 and electro-magnet 22 constitutes parts of a well-known type of winding machine.

The foot lever 1 is depressed to start the 80 machine, and the link 13 falls into the position shown in Fig. 2, causing the winding operation to continue until the kick-off lever is operated to release the same. It is, of course, to be understood that this kick-off 85 lever can be manually operated, and such is the common practice with machines of this type, and my invention consists solely in the automatic operation of said lever as will be explained. 90

24 represents a bifurcated bracket which may be secured to the machine in any approved manner, and which supports my improved electric contact fork 25. The fork 25 is pivotally supported between its ends 95 on a screw 26, and its upper bifurcated or forked end is adapted to receive the silk thread 27 as it passes to the spool 23.

The lower end of the fork engages a wire spring 28, exerting sufficient pressure against 100 the lower end of the fork to hold it in normal position during the ordinary operation, but when a knot or slub reaches the fork and cannot pass through the same, it will cause the fork to swing on its pivot, and compel the lower end of the fork to engage an electric contact 29 which is secured to a bolt 30, the latter insulated from bracket 24. 105

Bolt 30 extends through bracket 24, and is provided on its other end with a contact 31 110 which is adapted to be engaged by a wire lever 32. This lever 32 is pivotally sup-

ported between its ends as shown at 33, and at one end is provided with a hook portion 34 which is supported on the thread 27, so that when the thread breaks, or the end of 5 the thread is reached, the lever will pivot, and one end thereof will engage the contact 31.

A contact 35 is secured to the machine frame 36 and insulated from the latter, and 10 this contact is in position to be engaged by bar 8 when the latter is moved outwardly to operative position.

37 represents a source of electricity, and the electric circuit is as follows:—The battery or electric source 37 is connected by a 15 wire 38 with contact 35. The other side of the battery or source of electricity is connected by a wire 39 with one pole of magnet 22. The other pole of the magnet is 20 connected by a wire 40 with the bolt 30 which is electrically connected with both contacts 29 and 31. The bracket 24 and other parts of the machine constitute the ground, and in ordinary operation, the contact 35 is against bar 8. The circuit is, 25 however, broken by the position of the fork 25 and lever 32.

When a slab or knot strikes the fork 25 and causes it to pivot, it will engage contact 30 29, and the circuit will be as follows:—from battery 37, through wire 38, contact 35, and bar 8 to the ground. From the other side of the battery 37, through wire 25 39, electro-magnet 22, wire 40, contact 29, fork 25 to the ground.

Electro-magnet 22 will be energized so 35 that it will draw down lever 20, causing the lever 14 to elevate link 13, and allow spring 5 to withdraw the bar 8, which as above explained, causes the stopping of the winding machine.

As soon as the bar 8 moves away from 40 contact 35, the electric circuit is broken, and there can be no waste of current. The contact is made in like manner when the thread 27 breaks, or when the end of the thread is reached, as the lever 32 will engage contact 31 so that it will be seen that my improvements operate to stop the winding 45 to prevent the movement of a knot or slab onto the spool and also to stop the winding when a thread breaks.

The electric current cannot be wasted be-

cause whenever the circuit is closed, the magnet 22 will be energized to release the 55 kick-off lever 14, and the machine cannot be started until the fork 25 and lever 32 are moved away from their contacts 29 and 31.

While I have described my invention as taking a particular form, it will be understood that the various parts of my invention may be changed without departing from the spirit thereof, and hence I do not limit myself to the precise construction set forth, but consider that I am at liberty to 60 65 make such changes and alterations as fairly come within the scope of the appended claim.

Having thus described my invention, what I claim as new and desire to secure by 70 Letters Patent is:

In a winding machine, the combination 75 of a spring pressed bar movable by said spring to stop the machine; a link normally holding the bar against action of the spring; a kick-off lever having a portion for moving the link; an armature lever for moving the kick-off lever; a lever normally resting upon the thread; an electro-magnet for actuating the armature lever; a bracket having an electric contact thereon; a thread-guiding fork movably connected to the bracket and normally positioned away from the contact, said fork being movable by a knot or slab in the thread into engagement 85 with the contact; and a source of electricity included in circuit with said first mentioned contact, said magnet, and the fork, whereby when the fork engages said contact an electric circuit is completed and the spring 90 pressed bar is released by the link and moved by said spring to stop the machine, said second lever also being operative, when the thread is broken or discontinued thereunder, to engage said contact to complete 95 said electric circuit to stop the machine in said latter manner, substantially as described.

In testimony whereof I have signed my name to this specification in the presence of 100 two subscribing witnesses.

EDWARD D. GUDEBROD.
